UNITED STATES PATENT OFFICE.

EDWIN J. ARMSTRONG, OF ERIE, PENNSYLVANIA, ASSIGNOR TO ERIE STEAM SHOVEL COMPANY, OF ERIE, PENNSYLVANIA, A CORPORATION OF PENNSYLVANIA.

CONTROL MECHANISM.

Application filed April 5, 1924. Serial No. 704,417.

With the handling of power shovels, particularly where the different elements of the shaft are driven from the same source of power there has been some difficulty in so simplifying the control mechanisms that the operator standing in the single position could readily accomplish the various operations which it is desirable to perform. This is particularly so with relation to the control of the crowding and holding of the dipper stick. The present invention is directed to simplifying this control. Other details and features of the invention will appear from the specification and claims.

15 The invention is illustrated in the accompanying drawings as follows:

Fig. 1 shows a side elevation of a power shovel.

Fig. 2 a plan view of the same.

20 Fig. 3 a plan view of the crowding engine actuating drum showing the brake mechanism thereon.

Fig. 4 a section on the line 4—4 in Fig. 3.

25 Fig. 5 a side elevation, partly in section, of the valve mechanism controlling the clutches, connected with the drum actuating the dipper stick.

Fig. 6 a section on the line 6—6 in Fig. 5.

30 Fig. 7 a central section through the valve mechanism controlling the brake.

Fig. 8 a similar section showing a different position of the valve.

Fig. 9 a section on the line 9—9 in Fig. 8.

35 Fig. 10 a side elevation of the hand control lever for the brake valve.

Fig. 11 an end view of the guide plunger.

1 marks the turn table, or platform, 2 the truck frame, 3 the driving wheels, 4 the steering wheels, 5 the boom carried by the 40 platform, 6 the dipper stick, 7 the dipper, 8 a rack on the dipper stick, 9 a gear operating on the rack, 10 a shipper shaft carrying the gear 9 and 11 a bearing for the shipper shaft carried by the boom. The 45 shipper shaft is driven through a cable 12 which is wound and unwound from the drum 13 mounted on the shaft 10. The cable 12 extends to a drum 14 on the platform, one end being wound on this drum as the other 50 is wound off corresponding to the movement on the drum 13. The cable is drawn through the guide sheaves 12^a.

A hoisting line 15 extends over a sheave 16 at the top of the boom, the sheave 17 on

the dipper and to a drum 18 on the platform.

The motor, which as shown is an explosive engine 19, is mounted on the platform. The motor has a power wheel 20. A belt 21 takes the power from the wheel 20 and 60 communicates it to a pulley 22. The pulley 22 is mounted on a shaft 23 mounted in bearings 24 and 25 arranged on posts 24^a and 25^a extending upwardly from the platform. The shaft extends also to bearings 26 on posts 26^a. A gear 27 is fixed on the shaft 23 and meshes with a gear 30. The gear 30 is mounted on a shaft 31 carried in bearings 34 and 35 in the posts 24^a and 25^a and the bearing 36 in a post extending 70 upwardly from the frame. The drum 14 is slidingly mounted on a shaft 29. The shaft 29 is mounted in bearings 32 and 33 on the posts 24^a and 26^a respectively.

Fluid actuated clutches 37 and 38 are 75 mounted on the shafts 23 and 31 and lock or release gears 39 and 40 respectively with the shafts 23 and 31. Gears 39 and 40 mesh with a gear 41 fixed on the shaft 29. The gear web has openings 42 which are adapted to engage projections 43 on the drum so that the gear may be moved into and 80 out of engagement with the drum by an endwise movement of the gear 41 and this is accomplished by the sliding of the shaft 29 through a lever 29^a, the drum being retained in its position by a grooved collar 14^a into the groove of which extends a finger 14^b.

A bevelled gear 44 is locked with the gear 41 and is thrown to mesh with a gear 45 as the shaft is moved carrying the clutch projections 43 out of the openings 42. The gear 45 is fixed on a shaft 46. A bevelled gear 47 is also fixed on the shaft 46 and meshes with a bevelled gear 48. The bevelled gear 48 is fixed on a shaft 49 extending downwardly through the pivotal center of the machine. A bevelled gear 50 is fixed on the lower end of the shaft 49 and meshes with a bevelled gear 51. The bevelled gear 51 is fixed on a shaft 52. A bevelled gear 53 is also fixed on the shaft 52 and meshes with a gear 54. The bevelled gear 54 is fixed on the axle 3^a and the machine given 100 traction through this mechanism.

A gear 55 is fixed on the shaft 31 and meshes with a gear 56. The gear 56 is

adapted to be thrown into engagement with the drum 18 by means of the usual air controlled clutch 57. The clutch is controlled by a valve 58. The valve is controlled from 5 a link 59 extending to a control lever 60. A circle gear 61 is mounted on the truck 2 and a pinion 62 meshes with the gear 61 and moves with a gear 63. The gear 63 meshes with a gear 64. The gear 64 is carried by a 10 shaft 65 extending upwardly through the platform. A bevelled gear 66 is fixed on the shaft 65 and meshes with a gear 67. The gear 67 is fixed on a shaft 68 carried in bearings 69. A gear 70 is also fixed on the shaft 68. 15 Gears 71 and 72 mesh with the gears 70. Air clutches 73 and 74 are adapted to lock the gears 71 and 72 with the shafts 23 and 31. The air clutches are controlled by a valve 75 controlling the air through pipes 20 73^a and 74^a leading through the shafts to the clutches. The valve 75 is controlled by a hand lever 75^b through a link 75^a. An air pump 76 is driven from the power shaft of the engine and delivers air to a supply 25 tank 77 and from the supply tank to the valves 75 and 58. The air is also delivered to a controlling valve 78 controlling the clutches 37 and 38 by way of a supply pipe 80. The controlling valve 78 operates on a 30 seat 79 and is mounted in a chest 79^a. It has ports 81, 82 and 83. The port 83 is an exhaust port. The port 81 leads by a pipe 84 to a connection 85 in the end of the shaft 31 leading to the fluid-actuated clutch 38. 35 A pipe 86 leads from the port 82 to a connection 87 in the end of the shaft 23 and forms communication with the air-controlled clutch 37. Valve passages 88 and 89 extend through the valve 78. The passage 88 is 40 adapted to be brought into register with the port 81 and the passage 89 with the port 82 through the rocking of the valve, the ports 81 and 82 being a sufficient distance apart to give an extended travel in which the 45 ports 88 and 89 are out of register with both the ports 81 and 82 for a purpose hereinafter described. An annular groove 90 is arranged in the face of the valve and connects the exhaust port 83 with the ports 81 and 50 82 except when the valve is swung to the extreme positions to bring the passages 88 and 89 into register with the ports 81 and 82. 55 The valve is controlled by a rock shaft 91 journaled in a valve body 92, the valve body being secured to the platform frame. The rock shaft is driven by a lever 93 connected by a link 94 with a rock arm 95. The rock arm 95 is mounted on a shaft 96. A rock arm 95^a is fixed on the shaft 96 and connected by a link 98 with a rock arm 99. The rock arm 99 is mounted on a shaft 100 and is adapted to be controlled by a hand lever 101 arranged on the platform adjacent 60 to the control levers 60 and 75^b. It is desirable to control the brake for the drum 14 so as to hold the dipper stick in any position that may be desired and it is desirable to control the brake without additional levers and in the present invention this is accomplished with the same control lever as controls the valve 78 and consequently the clutches controlling the drum 14. The brake is shown in detail in Figs. 75 3 and 4. A brake drum 102 is carried by the drum 14. A brake band 103 operates on the brake drum. The pull end of the band has an eye 104 anchored on a pin 105. The pin is carried by a post 105^a extending from the post 24^a. A lever 106 is journaled on a pin 105 and has a pin 107 on which the eye 108 on the free end of the band is mounted. It will readily be seen that by swinging the lever 106 the 80 brake band may be tightened or loosened as desired. A push pin 109 extends from the lever 106 to a piston 110 arranged in a cylinder 110^a. The device just described forms a ram for actuating the brake lever. A spring 111 returns the lever and releases 85 the brake when the air is released from the ram. Air is delivered to the ram through a pipe 112. 90 Air to the ram is controlled by a brake valve. The pipe 112 leads to a passage 113 in the brake valve body 114. A supply pipe 115 leads from the pipe 80 to a passage 116 in the valve body. A check valve 117 operates on a seat 118 in the body and when released closes the air supply leading 95 through the passage 116, past the seat 118 to the passage 113 and hence to the ram. A trip pin 118^a is adapted to trip the check valve 117. The trip pin is mounted on a 100 plunger 119 carried in a guide passage 120. The plunger is reduced in the intermediate portions forming an annular passage around it and has the guide head 119^a with openings 121 to permit the passage of air to the 105 guide passage 120 and the passage 113. A valve 122 is arranged on the lower end of the plunger 119 and closes on a seat 123 on the valve body so that when the plunger is raised to trip the valve 117 the valve head 122 closes the lower end of the guide passage 110 115 120. The plunger 119 rests on a plunger extension 124. The plunger extension is carried in a guide 125 and extends into a head extension 126. The head extension extends from a head 126^a having a socket 128. The plunger extension has a plunger head 127 arranged in the socket and a spring 129 is arranged in the socket below the head 127 120 and tends to keep the head against the upper end of the socket. The spring is seated on a plug 130 in the lower end of the head which closes the socket, the plug carrying a cam 131 below the head. 125 130 A slot 132 extends across one side of the

head 126^a forming a shoulder 133 at the upper end of the slot. A shaft 134 is mounted in an opening 135 in the valve body and extends into the slot 132. The shaft is 5 cut away at its inner end forming a flat 136 which when turned upwardly forms a stop for the shoulder 133. A spring 136^a is arranged in the valve body and above the head 126^a and forces the head downwardly 10 so as to bring the shoulder 133 into contact with the shaft 134. When the flat 136 is swung upwardly the downward movement of the head is sufficient to permit the seating of the valve 117 but when the shaft 134 is 15 swung so that the round part of the shaft is upwardly as shown in Fig. 9 the valve 117 is tripped and the valve 122 is closed. A hand lever 137 is arranged on the shaft 134 by which it may be readily swung and 20 the shaft is held in the opening by a cap 138.

A cam 139 is mounted on the link 94 and is in the path of the cam 131 when the lever 93 is swung through the action of the control lever 101. The cam 139 is entirely disengaged from the cam 131 when either the valve passage 88 or 89 is in register with the ports 81 or 82 respectively and the cam action controlling the brake is operative, 30 therefore, in the neutral position and the control lever between those positions which throw the air on to one or the other of the air clutches 37 and 38. The operator, therefore, if he wishes to set the brake swings 35 the control lever after releasing the clutches to an intermediate position which will set the brake. In order to apprise the operator of the right positioning of the cam 139 under the cam 131 to lock the brake a flat 40 is arranged on the top of the cam with a slight projection 140. The operator can by feel tell that the cam has reached the flat and when it reaches the shoulder 140 can 45 know that the brake is set requiring no further effort so far as holding the control lever is concerned. If the operator does not desire to set the brake and to have both clutches 37 and 38 released he swings the 50 valve sufficiently to bring the passage 88, or 89 out of register with the port 81, or 82 as the case may be but does not bring the cam 139 under the cam 140. The added movement for the passage 88 and 89 between 55 the ports 81 and 82 permits of these several intermediate positions of the control lever so as to control the clutches and brake as desired.

What I claim as new is:—

1. In a control mechanism, the combination of a controlled member; a reversing device actuating the controlled member; fluid actuated clutches controlling the reversing device; a brake for said controlled member; a valve mechanism controlling the clutches, said valve mechanism setting a

clutch at each extreme position and the brake at an intermediate position; and a single manually actuated means actuating the valve mechanism.

2. In a control mechanism, the combination of a controlled member; a reversing device actuating the controlled member; fluid actuated clutches controlling the reversing device; a brake for said controlled member; a valve mechanism controlling the clutches, 70 said valve mechanism setting a clutch at each extreme position and the brake at an intermediate position and having neutral positions relieving both clutches and the brake between each extreme position and the intermediate position; and a single manually actuated means actuating the valve mechanism.

3. In a control mechanism, the combination of a controlled member; a reversing device actuating the controlled member; fluid actuated clutches controlling the reversing device; a brake for said controlled member; a valve mechanism controlling the clutches, said valve mechanism setting a clutch at each extreme position and the brake at an intermediate position and having neutral positions relieving both clutches and the brake between each extreme position and the intermediate position; and a single manually actuated means actuating the valve mechanism, 80 said valve mechanism and means indicating from a sense of touch the setting of the valve mechanism.

4. In a control mechanism, the combination of a controlled member; a reversing device actuating the controlled member; fluid actuated clutches controlling the reversing device; a brake for said controlled member; a valve mechanism controlling the clutches, 100 said valve mechanism setting a clutch at each extreme position and the brake at an intermediate position and having neutral positions relieving both clutches and the brake between each extreme position and the intermediate position; and a single manually actuated means actuating the valve mechanism, said valve mechanism comprising devices varying the resistance to its movement indicating by the sense of touch on said means the setting of the valve mechanism.

5. In a control mechanism, the combination of a controlled member; a reversing device actuating the controlled member; fluid actuated clutches controlling the reversing device; a brake for said controlled member; a valve mechanism comprising a valve device controlling the clutches and setting the same at the extreme throw of the valve mechanism; and a cam-actuated valve controlling the brake; the cam being engaged at an intermediate point in the throw of the valve mechanism.

6. In a control mechanism, the combination of a controlled member; a reversing

- device actuating the controlled member; fluid actuated clutches controlling the reversing device; a brake for said controlled member; a valve mechanism comprising a valve device controlling the clutches and setting the same at the extreme throw of the brake mechanism; and a cam-actuated valve controlling the brake, the cam being engaged at an intermediate point in the throw 10 of the valve mechanism with intervening neutral positions of the valve mechanism between the extremes and the point at which the cam is engaged, said neutral positions releasing both the brake and the clutches.
- 15 7. In a control mechanism, the combination of a controlled member; a reversing device actuating the controlled member; fluid actuated clutches controlling the reversing device; a brake for said controlled device; a valve mechanism comprising a valve device controlling the clutches and setting the same at the extreme throw of the valve mechanism; and a cam actuated valve controlling the brake, the cam being engaged at an intermediate point in the throw of the valve mechanism, the engagement of the cam indicating to the touch the setting of the valve mechanism to set the brake. 8. In a control mechanism, the combination 30 of a controlled member; a reversing device actuating the controlled member; fluid actuated clutches controlling the reversing device; a brake for said controlled device; a valve mechanism comprising a rotary valve controlling the clutches and setting the same at the extremes of the throw of the valve mechanism; and a cam-actuated valve controlling the brake, the cam being engaged at an intermediate part of the throw of the valve mechanism and operating the cam with a throw from either direction, the resistance of the cam indicating by a sense of touch the position of the valve mechanism. 9. In a control mechanism, the combination 45 of a controlled member; a reversing device actuating the controlled member; fluid actuated clutches controlling the reversing device; a brake for said controlled member; a valve mechanism comprising a valve device controlling the clutches and setting the same at the extreme throw of the valve mechanism; a cam-actuated valve controlling the brake, the cam being engaged at an intermediate point in the throw of the valve mechanism; and a single manually actuated means for actuating the valve mechanism. 50 10. In a control mechanism, the combination 60 of a controlled member; a reversing device actuating the controlled member; fluid actuated clutches controlling the reversing device; a brake for said controlled device; a valve mechanism comprising a valve device controlling the clutches and setting the same at the extreme throw of the valve mechanism; a cam-actuated valve controlling the brake, the cam being engaged at an intermediate point in the throw of the valve mechanism with intervening neutral positions of the valve mechanism between the extremes and the point at which the cam is engaged, said neutral positions releasing both the brake and the clutches.
- 55 11. In a control mechanism, the combination of a controlled member; a reversing device actuating the controlled member; fluid actuated clutches controlling the reversing device; a brake for said controlled member; a valve mechanism comprising a valve controlling the clutches and setting the same at the extreme of the throw of the valve mechanism; a check valve controlling the brake; and a cam actuated means tripping the check valve to set the brake. 60 12. In a control mechanism, the combination of a controlled member; a fluid actuated clutch controlling said member; a fluid actuated brake for said member; a valve mechanism controlling the clutch and brake; a single manually actuated means actuating the valve mechanism; and an independent means controlling the brake. 65 13. In a control mechanism, the combination of a controlled member; a reversing device actuating the controlled member; fluid actuated clutches controlling the reversing device; a brake for said controlled member; a valve mechanism controlling the clutches, said valve mechanism setting a clutch at each extreme position and the brake at an intermediate position; a single manually actuated means actuating the valve mechanism; and independent means controlling the brake while permitting the control of the clutches. 70 14. In a control mechanism, the combination of a controlled member; a reversing device actuating the controlled member; fluid actuated clutches controlling the reversing device; a brake for said controlled member; a valve mechanism comprising a valve controlling the clutches and setting the same at the extremes of the throw of the valve mechanism; a valve controlling the brake comprising a valve; a plunger operating the valve; a spring acting on the plunger to close the valve; and a cam acting on the plunger and actuated at an intermediate point in the throw of the valve mechanism. 75 15. In a control mechanism, the combination of a controlled member; a reversing device actuating the controlled member; fluid actuated clutches controlling the reversing device; a brake for said controlled member; a valve mechanism comprising a valve controlling the clutches and setting the same at the extremes of the throw of the valve mechanism; a valve controlling the brake comprising a check valve; a plunger 80

tripping the check valve; a valve carried by the plunger opening and closing the exhaust alternately with the tripping of the check valve; a yielding mounting for the plunger; a spring operating against the plunger; a cam on the plunger engaged at an intermediate position of the throw of the valve mechanism; and independent means for locking the plunger to hold the plunger in position to trip the check valve to set the brake.

16. In a control mechanism, the combination of a controlled member; a reversing device actuating the controlled member; fluid actuated clutches controlling the reversing device; a brake for said controlled member; a valve mechanism comprising a valve controlling the clutches and setting the same at the extremes of the throw of the valve mechanism; a valve controlling the brake comprising a plunger; a cam on the plunger engaged at an intermediate position of the throw of the valve mechanism to open the valve to set the brake; a spring opposing the cam movement; a slot in the plunger; a cam operating in the slot; and means for throwing the cam to lock the plunger in position to open the valve independently of the cam.

17. In a control mechanism, the combina-

tion of a controlled member; a reversing device actuating the controlled member; fluid actuated clutches controlling the reversing device; a brake for said controlled member; a valve mechanism comprising a valve controlling the clutches and setting the same at the extreme of the throw of the valve mechanism; and a cam actuated valve controlling the brake, the cam being engaged at an intermediate part of the throw of the valve mechanism and having a step thereon for holding the valve in open position.

18. In a control mechanism, the combination of a controlled member; a reversing device actuating the controlled member; fluid actuated clutches controlling the reversing devices; a brake for said controlled member; a valve mechanism comprising a valve controlling the clutches and setting the same at the extreme of the throw of the valve mechanism; a cam actuated valve controlling the brake, the cam being engaged at an intermediate part of the throw of the valve mechanism and having a step thereon for holding the valve in open position; and an obstruction indicating to a sense of touch the positioning of the cam on the step.

In testimony whereof I have hereunto set my hand.

EDWIN J. ARMSTRONG.
